BUILDING BLOCK

Harold S. Boutin, P.R. 2, Box 238, Curtice, Ohio

Filed Aug. 29, 1960, Ser. No. 61,928

Term of patent 14 years

(Cl. D18—2)

FIG. 1 is a view in front elevation of a building block showing my new design;

FIG. 2 is an end view in elevation taken from the right side of FIG. 1;

FIG. 3 is a top plan view of the block shown in FIG. 1;

FIG. 4 is a view in perspective and on an enlarged scale of the building block shown in FIG. 1.

I claim:

The ornamental design for a building block, as shown.
